TIMING DEVICE

Edward S. Peterson, Elmwood Park, Ill., assignor
to Automatic Electric Laboratories, Inc., Chi-
cago, Ill., a corporation of Delaware

Application June 26, 1944, Serial No. 542,178

1 Claim. (Cl. 200—97)

1

The present invention relates to timing devices in general, and more particularly to a new and improved timing device for electrical circuits which is economical in operation, highly accurate, shock proof, unaffected by temperature conditions, and non-positional in mounting characteristics.

One object of the invention is to provide a timing device that is non-stallable in any position. Such a device is particularly adapted for use on aircraft, ships and other like applications where plumb and level conditions are not stable. There are also many other application requirements which necessitate mounting the timing device in the position best suited for the individual application.

Another object of the invention is to provide accurate timing through the media of new and novel means of associating a clockwork mechanism with a solenoid control, the particular arrangement including means for causing switch contacts to be operated after a predetermined interval of time has been accurately timed by the clockwork mechanism.

A further object of the invention is to provide new and novel means for resetting the clockwork mechanism should the circuit conditions controlling the timing device change before the clockwork mechanism has operated for a predetermined interval of time. No change is made in the position of switch contacts under such conditions until the clockwork mechanism has operated for the full predetermined interval of time, irrespective of the number of incomplete attempts made by the clockwork mechanism.

Another object of the invention is to operate the timing device economically. As is well known, a solenoid requires considerably more power for its energization than is required to maintain the solenoid in the energized, or holding, position. The invention, therefore, includes means for reducing the current flow through the coil of the solenoid after the coil is fully energized and until the circuit of the coil is broken. Consequently, a saving in current consumption is effected when the holding periods of the solenoid are of longer duration than the time required to energize the solenoid, such a situation prevailing in many cases.

In order to accomplish the above described objects, the timing device consists essentially of a clockwork mechanism for accurately timing a predetermined interval of time, new and novel means controlled by a solenoid for causing the clockwork mechanism to operate for the predetermined interval, and means for operating

2

switch contacts after the clockwork mechanism has completed the timing.

A feature of the invention is that the timing device is universal in mounting application and, consequently, may be mounted in the position best adapted for each particular installation. This non-positional mounting feature is made possible by the particular design of the coupling between the clockwork mechanism and the plunger of the solenoid, this coupling being self-aligning under all conditions and employing no links, guides or other mechanical devices which may be affected by gravity in relationship to the particular mounting position, or become jammed as a result of unnatural strains.

Another feature of the invention is that the coupling between the clockwork mechanism and the plunger of the solenoid includes an arbor so connected with both units that the solenoid plunger, as it is drawn into the coil of the solenoid, correspondingly turns the arbor to tension a power spring, and, when the circuit of the solenoid coil is opened, the tensioned power spring causes the arbor to turn in the opposite direction for driving the clockwork mechanism and for gradually withdrawing the plunger until the plunger reaches a stop limiting its outward movement, the clockwork mechanism regulating the speed of withdrawal. A simple and positive action for setting the clockwork mechanism is thus assured without requiring complicated adjustments or lubrication. The coupling arrangement also permits the solenoid to reset the clockwork mechanism at any instant before the clockwork mechanism has operated for the full predetermined interval of time.

Another feature of the invention is that means is provided for so adjusting the normal tension of the power spring that the drawing in of the solenoid plunger responsive to the energization of the solenoid coil will properly tension the power spring for driving the clockwork mechanism and withdrawing the plunger from the solenoid coil when the circuit of the solenoid coil is opened.

Another feature of the invention is that the length of the interval timed by the clockwork mechanism may be adjusted to suit the requirements of each particular installation. Adjustments are made by changing the position of the lever operating the switch contacts.

Another feature of the invention is that the switch operated by the timing device may be of either the snap action (quick break and/or make) type or of the well known telephone relay contact spring type, and may be fitted with single

or multiple poles and be single or double throw.

Another feature of the invention is that economical operation of the timing device is achieved through the use of a resistor which is switched in series with the coil of the solenoid when the solenoid is in the energized position. The reduction of current consumption during the periods that the solenoid is held in the energized position represents a direct saving because in many timing installations the holding periods are longer than the time required to energize the solenoid coil.

There are other objects and features of the invention having to do for the most part with the circuit and mechanical details involved in carrying out the foregoing. The various objects and features of the invention will be understood best upon a further perusal of the description in connection with the accompanying drawings.

The invention is disclosed in two sheets of drawings comprising Figs. 1 to 6, inclusive. Fig. 1 is a side view of the timing device, in elevation, showing the general relationship of the solenoid coil, solenoid plunger, arbor, and clockwork mechanism, and also illustrating the attachment of a power spring between the arbor and an adjustable bracket mounted on the base plate supporting the solenoid structure; Fig. 2 is a top view of the device, in elevation, showing the general arrangement of the switches with respect to the arbor and its associated members for operating the switches; Fig. 3 is a side view, in elevation, opposite to the view shown in Fig. 1 and shows means for adjusting the outward movement of the solenoid plunger and also the location of the resistance coil wired in series with the coil of the solenoid; Fig. 4 is a partial top view, in elevation, for illustrating how a snap action (quick break and/or make) type of switch, such as the well known cantilever midget power switch, may be employed in place of the conventional relay contact spring assembly shown in Fig. 2; Fig. 5 is an enlarged sectional view looking down on the solenoid plunger meshed with its associated gear wheel mounted on the arbor, this view also showing the attachment of the power spring to a plate member of the arbor; and Fig. 6 diagrammatically illustrates the general circuit arrangement in association with the major apparatus units.

Referring now to Figs. 1 to 6, inclusive, a detailed description will be given of the mechanical arrangement of the timing device, after which will follow a description of the operation.

The timing device consists essentially of a switch 1 connected in the circuit of a given application in which a predetermined time delay is required before the operation of switch 1 changes the circuit conditions it controls, a rotating arbor 2 with an associated member 3 for operating switch 1, a solenoid coil 6 controlling the movement of a plunger 7 gear coupled to arbor 2, a power spring 11 attached to a circular plate member 13 of arbor 2, and a clockwork mechanism 17 coupled to arbor 2 through the medium of a ratchet device 14. When the circuit of solenoid coil 6 is closed by means of a control circuit, plunger 7 is drawn quickly into the solenoid 6 and correspondingly rotates arbor 2 through a given arc by means of gear coupling 12. This rotation of arbor 2 tensions power spring 11 through the medium of a plate member 13, and also moves member 3 from switch 1. When solenoid coil 6 is deenergized by the opening of the control circuit, power spring 11 causes the rotation of arbor 2 in the opposite direction

because plunger 7 is no longer held by magnetic attraction and, consequently, plunger 7 is withdrawn from solenoid coil 6 through the medium of gear coupling 12. The withdrawal of plunger 7 is gradual instead of instantaneous because ratchet 14 now couples the clockwork mechanism 17 fixedly with arbor 2 with the result that the clockwork mechanism 17 controls the return movement of arbor 2. Hence, member 3 will not reach and operate switch 1 until the clockwork mechanism has operated for the predetermined time interval.

It should be understood at this time that the timing device arrangement outlined in the preceding paragraph is but one embodiment of the invention, and that various changes or modifications may be carried out to accomplish desired arrangements, as will be apparent to those skilled in the art. It is also obvious that the time delay may be used for retarding the magnetic attraction of the plunger instead of delaying the outward movement of the plunger.

The length of time the clockwork mechanism 17 is permitted to operate by spring power when solenoid coil 6 is deenergized, is controlled by fitting the clockwork mechanism with the proper gear train to establish the desired time interval. Supplementary adjustment may be made by adjusting the stop 24 which limits the outward movement of plunger 7. The plunger stop arrangement is illustrated in Fig. 3 and also in the enlarged sectional view of Fig. 5. Bracket 20 attached to the mounting plate supporting switch 1 provides firm anchorage for stop screw 24, and nut 22 locks the stop screw in place.

The arbor 2 includes an upper shaft and a lower shaft, the lower shaft being partly telescoped within the upper shaft and coupled thereto by means of ratchet 14. The telescoping is done on a loose fit basis so that the upper shaft serves as one bearing for the lower shaft, and vice versa. A second bearing for each shaft is included respectively in the upper and lower mounting plates supporting the solenoid structure. The toothed wheel of ratchet 14 is attached solidly to a hub of the lower shaft, and the pawl of ratchet 14 is attached to a plate member 13 of the upper shaft and kept in contact with the toothed wheel by means of a curved flat spring. The toothed wheel 14 may be identified in Fig. 1 and the pawl and spring 14 in Fig. 3. The lower shaft is also permanently coupled to the driving arbor of clockwork mechanism 17, and the upper shaft carries a member 3 for operating switch 1. The purpose of ratchet 14 is to permit slippage between the upper and lower shafts when the upper shaft is caused to rotate by means of the gear coupling 12 as plunger 7 is moved inward by magnetic attraction, and to fixedly couple the upper and lower shafts together when the upper shaft is rotated in the opposite direction by power spring 11 so that both shafts then rotate as one unit. The clockwork mechanism 17 is, therefore, operated only when ratchet 14 transmits the energy of power spring 11 from the upper shaft to the lower shaft.

It is of particular interest that the coupling means between solenoid plunger 7, arbor 2 with its two shafts and ratchet 14, and clockwork mechanism 17 is self-aligning at all times, and includes no links, guides or other similar devices which may be affected by gravity if the mounting position with respect to plumb and level conditions is not maintained. It should be understood, however, that other well known methods of coupling

two shafts together so that only one shaft rotates when the rotation is in one direction and both shafts rotate as one unit when the rotation is in the opposite direction, are equally as adaptable as the particular coupling just described.

One end of the power spring 11 is attached to plate member 13 of the upper shaft of arbor 2, and the other end to an adjustable bracket 16, as shown in Fig. 1. The adjustable bracket 16 is slotted in order that it may be moved forward or backward lengthwise on the lower mounting plate 15 supporting the solenoid structure, thus permitting the normal tension of spring 11 to be correspondingly decreased or increased. Screws are provided for securing bracket 16 in the adjusted position. The driving tension for spring 11 is obtained when arbor 2 is rotated clockwise (looking at the top view of Fig. 2) by the magnetic attraction of plunger 7. The normal tension is so adjusted that the maximum driving tension will not overcome the magnetic attraction of plunger 7.

The time interval required for arbor 2 to move member 3 into mechanical contact with switch 1 after solenoid coil 6 is deenergized, may be varied by changing the position of member 3 on arbor 2, a locking means 19 (Fig. 1) permitting the loosening and fixing of member 3. Moving member 3 in the direction of switch 1 will shorten the time interval and, conversely, moving member 3 in the direction away from switch 1 will increase the time interval.

The blades of switch 1 shown in Fig. 2 are of the well known relay twin contact spring type. The particular combination illustrated is double pole double throw, but it is obvious that any desired contact combination may be provided in either single pole or multiple pole. The speed of the switch contact operation with this type of contact spring is determined by the speed of travel of member 3 under the control of clockwork mechanism 17, the contact movement being relatively slow or rapid as the case may be. When circumstances require switch contacts with snap action (quick break and/or make), switch 1 may be any suitable well known snap switch, such as, for example, the cantilever type of midget power switch illustrated in Fig. 4.

Resistor 8, the location of which is shown in Figs. 2 and 3, is provided for the purpose of reducing the current flow through solenoid coil 6 after solenoid coil 6 is fully energized and for the subsequent period solenoid coil 6 remains energized. It is a well known fact that a solenoid coil requires considerably more power to attract a plunger magnetically than is required to maintain the plunger in the attracted position. A saving in current consumption is, therefore, accomplished by increasing the resistance value of the solenoid coil circuit during the periods the plunger is in the attracted position, when such "holding" periods are longer than the time required to attract the plunger, which situation is prevalent in many timing applications. Resistor 8 is wired in series with solenoid coil 6 but is normally shunted by the contacts of switch 5, as shown in Fig. 6. When solenoid coil 6 is energized and attracts plunger 7, member 4 attached to arbor 2, as shown in Fig. 2, is moved towards switch 5, and reaches and operates switch 5 just before plunger 7 reaches its innermost position. The operation of switch 5 removes the shunt from resistor 8, and the resistance value of the circuit of solenoid coil 6 is increased by the resistance value of resistor 8, thereby reducing the current flow through sole-

noid coil 6. When the circuit of solenoid coil 6 is opened, member 4 is moved away from switch 5 by arbor 2, and the closing of the contacts of switch 5 re-establishes the shunt around resistor 8 and thereby decreases the resistance value of the energizing circuit of solenoid coil 6 to normal.

While Fig. 6 indicates that switch 5 is used for the purpose of reducing the current flow through solenoid coil 6 when plunger 7 is fully attracted, it should be understood that switch 5 may be fitted with any desired contact arrangement and used for performing other switching operations associated with the timing application. Thus it is possible to construct the timing device to operate switch 5 when solenoid plunger 7 is magnetically attracted, this operation being practically instantaneous, and then operate switch 1 after a desired interval of time has lapsed, as controlled by clockwork mechanism 17, both switches controlling switching operations associated with the timing application. It is also possible to reverse the time delaying operation so that switch 5 is not operated until the predetermined interval of time has lapsed and then operate switch 1 immediately after the circuit of solenoid coil 6 is opened.

In view of the foregoing description it is believed that the invention can be most readily made clear by describing its mode of operation in a typical application.

Referring now to Fig. 6, it will be assumed that the particular installation includes a contact switch 10 which is closed and opened at certain intervals for controlling the operation of the timing device, and a source of power supply 9 wired in series with solenoid coil 6 of the timing device and contact switch 10. Also, the circuits to be controlled by the timing device require that switch 1 be fitted with double-pole double-throw contact blades as shown. The circuits to be controlled by the timing device are connected to terminals 23 shown in Figs. 1, 2 and 3, the terminals 23 being wired to the contact blades of switch 1. Solenoid plunger 7 is coupled to arbor 2 in the manner previously described so that member 3 attached to arbor 2 is normally in mechanical contact with switch 1, and member 4 attached to arbor 2 is normally away from switch 5.

The closing of contact switch 10 connects power source 9 to solenoid coil 6 and, since resistor 8 is shunted by the contacts of switch 5, solenoid coil 6 magnetically attracts plunger 7. The inward movement of plunger 7 causes arbor 2 to rotate in a clockwise arc for moving member 3 from mechanical contact with switch 1 and for causing member 4 to operate switch 5, these operations requiring very little time. The removal of member 3 from switch 1 permits switch 1 to operate by its own spring power to break its normally closed contacts and make its normally open contacts for accomplishing certain circuit changes in the timing installation. The operation of switch 5 by member 4 occurs just before plunger 7 has completed its inward movement and opens the shunt across resistor 8, which action correspondingly increases the resistance of the circuit of solenoid coil 6 and thus reduces the current consumption of solenoid coil 6. The inward movement of plunger 7 by magnetic attraction also causes arbor 2 to tension power spring 11 (shown in Fig. 1) to provide power for rotating arbor 2 in the opposite direction when plunger 7 is freed from magnetic attraction, and for driving clockwork mechanism 17 during the return movement of arbor 2.

The plunger 7 is retained in the attracted position until contact switch 10 of the timing installation is operated to open the circuit of solenoid coil 6. When the circuit of solenoid coil 6 is opened, plunger 7 is freed from further magnetic attraction and, consequently, power spring 11 (shown in Fig. 1) overcomes the inertia of plunger 7 and starts the rotation of the upper shaft of arbor 2 in the reverse direction. Immediately the upper shaft of arbor 2 starts to rotate in the reverse direction, ratchet 14 (Figs. 1 and 3) fixedly connects the upper and lower shafts of arbor 2 together so that both shafts will rotate as one unit. Hence, power spring 11 drives clockwork mechanism 17 through the combination of the upper shaft of arbor 2, ratchet 14, and the lower shaft of arbor 2. Arbor 2 can, therefore, rotate on its return movement only at the rate of speed permitted by the gear ratio of clockwork mechanism 17.

The return movement of arbor 2 accomplishes several results as follows:

1. The moving of member 4 from mechanical contact with switch 5, thus permitting switch 5 to close its contacts for again shunting resistor 8 and thereby restoring the original resistance condition to the circuit of solenoid coil 6. This action occurs almost immediately when the return movement of arbor 2 is started, the exact time required being dependent upon the speed of the return movement as regulated by clockwork mechanism 17. The position of member 4 on the upper shaft of arbor 2 may be changed to vary the point at which switch 5 is contacted and freed, locking means 18 (Fig. 1) permitting the loosening and fixing of member 4.

2. The gradual moving of member 3 towards switch 1 until member 3 operates switch 1, as regulated by clockwork mechanism 17. Member 3 reaches and operates switch 1 at the expiration of a certain predetermined interval of time after the opening of the circuit of solenoid coil by contact switch 10.

3. The gradual withdrawal of plunger 7 from solenoid coil 6 until the outer end of plunger 7 reaches stop 21 (Figs. 3 and 5). Plunger 7 reaches stop 21 at the expiration of the interval of time clockwork mechanism 17 is to be permitted to operate. The interval of time clockwork mechanism 17 is permitted to operate continues until member 3 has operated switch 1. When member

3 has operated switch 1, plunger 7 reaches stop 21, this action preventing further movement of arbor 2 and clockwork mechanism 17.

4. The operation of switch 1 by member 3 restores the circuits of the timing installation controlled by the timing device to the original arrangement prevailing at the time the circuit of solenoid coil 6 was closed by power switch 10.

What is claimed is:

- 10 In a timing mechanism, the combination of a solenoid having a plunger, an adjustable stop for providing an outward plunger movement of desired length, means for energizing and deenergizing said solenoid at certain intervals, a switch for controlling an electric circuit or circuits, a gear train, a spring, rotatable means, said plunger drawn into said solenoid by the energization of said solenoid for causing one operation of said rotatable means to tension said spring, said tensioned spring responsive to the deenergization of said solenoid causing another operation of said rotatable means to move said plunger outwardly to said stop, means for coupling said gear train with said plunger only when said plunger is moved outwardly to delay said plunger reaching said stop for a definite period of time, the arresting of said outward movement of said plunger causing the operation of said switch providing that said plunger reaches said stop before said solenoid is again energized and again attracts said plunger, the re-attraction of said plunger before said plunger reaches said stop preventing the operation of said switch, causing said coupling means to be temporarily disconnected from said gear train, and causing said rotatable means to retension said spring.
